UNITED STATES PATENT OFFICE.

ALFRED J. MACY, OF CHICAGO, ILLINOIS, ASSIGNOR TO MACY ART PROCESS CORPORATION, OF CHICAGO, ILLINOIS, A CORPORATION OF ILLINOIS.

INSERT TAB.

Application filed July 29, 1920, Serial No. 399,781. Renewed August 28, 1922. Serial No. 584,764.

To all whom it may concern:

Be it known that I, ALFRED J. MACY, a citizen of the United States, and a resident of the city of Chicago, in the county of Cook 5 and State of Illinois, have invented certain new and useful Improvements in an Insert Tab; and I do hereby declare that the following is a full, clear, and exact description of the same, reference being had to the accompanying drawings, and to the numerals 10 of reference marked thereon, which form a part of this specification.

This invention relates to an insert tab and provides means whereby thin articles which 15 are to be used in connection with the examination of books, magazines, circulars and the like may be removably secured therein. In the examination of books, magazines, circulars and the like it is often necessary or desirable 20 to use certain accessory articles such as cards having tables printed thereon, index slips, or in certain instances colored goggles which are made by securing pieces of transparent material in apertures in thin 25 flexible strips. When these articles are necessary for use in connection with the book or magazine that is being examined, it is often desirable that they be secured therein when not in use. This is especially true of 30 the two color flexible goggles which are used in the examination of colored stereoscopic pictures.

It is an object, therefore, of this invention to provide means whereby thin articles may 35 be removably secured in books, magazines, circulars and the like.

It is an important object of this invention to provide means which are formed in one leaf of a book, magazine, or the like, whereby 40 thin articles may be secured therein and whereby said articles may be conveniently removed therefrom, when said book or magazine is opened for examination.

Other and further important objects of 45 this invention will be apparent from the disclosures in the specification and the accompanying drawings.

The invention (in a preferred form) is shown on the drawings and hereinafter more 50 fully described.

On the drawings:

Figure 1 is a view in elevation showing an adaptation of the device of this invention.

Figure 2 is an enlarged fragmentary section on line 2-2 of Figure 1.

Figure 3 is a fragmentary elevation showing an insert tab embodying the principles of this invention.

As shown on the drawings:

The insert tab of this invention is conveniently formed by providing a V-shaped slit in the leaves of a book or magazine, preferably near the hinged portion thereof. Said slit is shown in Figure 3 and indicated by the reference numeral 1, a tab formed thereby being indicated by the reference numeral 2, while 3 indicates the leaf of the book, circular or magazine. Figure 1 shows the insert tab 2 in use with a pair of flexible goggles 4 inserted thereunder. Due to the fact 70 that the insert tab is ordinarily placed near the hinged portion of the leaf of the book, it is apparent that opening the book will act to raise said tab slightly away from the leaf from which it is formed due to the flex- 75 ing of the leaf caused by opening the same, thus facilitating the insertion of articles thereunder and the removal of articles therefrom. When the book or magazine is closed the flexible articles are of course locked in 80 position by the pressure of the same on the tab 2 and against the junction of the pages 3. While a V-shaped incision has been shown herein, it is apparent that the particular shape of the incision might be changed to 85 provide an insert tab for the same purpose and fall well within the spirit of this invention.

The incision which is made to provide the insert tab 2 does not interfere with the printing or decorating of the page 3 and for this reason provides a particularly desirable means for securing thin articles thereto.

I am aware that details and modifications may be varied through a wide range without departing from the principles of this invention, and I therefore do not purpose limiting the patent granted otherwise than necessitated by the prior art.

I claim as my invention:

1. The combination with a book, magazine or the like, having normally plane leaves of inwardly directed securing means associated with a leaf thereof, said securing means acting to rise from the plane of the 105 leaf upon flexing of the leaf, thereby facilitating the insertion of thin articles thereunder or the removal of the same therefrom.

2. The combination with a book, magazine, or the like, of an insert tab formed ad- 110

5 jacent the hinged portion of one of the leaves thereof for removably securing thin articles therein, said insert tab acting to rise above the plane of the leaf from which it is formed when the book or the magazine is opened.

10 3. In a volume, leaves, normally plane but becoming curved near the bound edges thereof when the volume is opened, one of said leaves having a cut forming a tab with its free end toward the bound edge of the leaf, said cut being located in that part of the leaf which becomes curved when the volume is opened, whereby on opening the volume at 15 said leaf the end of said tab will project from the surface of the leaf.

4. A card, transparent eye places in said card, a notch for the nose in one edge of the card between the eye places, in combination 20 with a book cover having a flap on the inner side thereof so located that there is only

room between the back of said flap and the binding edge of said cover for the narrow part of said card produced by said notch.

5. In combination, a leaf, having a tab 25 with its free end toward the bound edge of said leaf, and an object of sheet material, having a notch in one edge, the distance of the tab from the bound edge of the leaf being such that, when the object is inserted beneath the tab with the notch against the non-free end of the tab, the opposite edge of the object will be adjacent the bound edge of the leaf.

30 In testimony whereof I have hereunto subscribed my name in the presence of two subscribing witnesses.

ALFRED J. MACY.
